YARDAGE CONTROL MECHANISM

John H. Garrott, Bloomfield, N. J., assignor to
 The Clark Thread Company, Newark, N. J., a
 corporation of New Jersey

Application December 17, 1943, Serial No. 514,600

10 Claims. (Cl. 242—39)

The object of the invention is an improved yardage control mechanism for yarn winders.

The customary method of controlling the operation of yarn winders to bring the spindle drive to rest when the desired yardage has been wound has involved the use of some sort of feeler bearing on the package and acting to trip a spring-operated release mechanism to disengage a clutch drive when the diameter of the package has built up to a predetermined size. Among the objections to such types of device may be mentioned the difficulty of obtaining, and maintaining, accurate control of the actual yardage wound.

According to the present invention the winder control is effected not by mechanism dependent upon the size of the wound package in terms of its diameter but by release mechanism responsive to a predetermined number of revolutions of the spindle and in such manner as to hold the yardage content of the packages within extremely small limits of variation. Also, the invention provides a control mechanism which is simple and virtually fool-proof, and which requires no resetting or that the operator perform any other than standard operations in supervising the machines.

These and other objects and advantages of the invention will be apparent from the following description and the accompanying drawings in which a preferred form of the invention is shown applied to a Universal winder.

In the drawings, Fig. 1 is an elevation of so much of the winder as is necessary to illustrate the application of the invention, the parts being in the "running" position; Fig. 2 is a similar view but in the "at rest" position; Fig. 3 is a plan view showing, among other things, the drive take-off for the control mechanism; and Figs. 4 and 5 are broken views, in elevation, showing certain of the elements of Figs. 1 and 2 in different positions or stages of operation.

Being of familiar construction, only so much of the winder will be described as is necessary to an understanding of the invention. As will be recognized, the illustrated winder includes a spindle 1 and drive shaft 2, rotation of the spindle and shaft being controlled by handle 3 which is rotatable from the Fig. 2, or "at rest" position, to the Fig. 1, or "running" position, to start the winder. The handle rotates on the axis of a shaft 4 and is normally locked in its running position by suitable detent mechanism consisting of a latch piece 5 on arm 6, which latch piece is adapted to engage behind the cooperating latch or shoulder 7 formed on an upstanding portion of the arcuate arm generally designated 8. As usual, this arm is pivotally mounted at 9 and biased to hold the latch piece and shoulder in engagement to lock the handle and hence the associated winder drive in the running position

(Fig. 1). When the detent mechanism is released the winder (including spindle 1 and drive shaft 2) is brought to rest by the action of the customary spring-relieved clutch.

In Fig. 1 the path of the yarn 10 over guide 11 and under drop wire 12 to the spindle will also be recognized as of standard construction.

According to the preferred form of the invention there is provided what for convenience will be designated a timer wheel, which consists of any appropriate rotary member so geared to the winder as to make exactly one revolution during the winding of a complete package. In the illustrated form the timer wheel consists of a pair of spaced discs 13 carried on a hub 14 which is itself mounted on a shaft 15. Also mounted on the shaft and appropriately locked to the timer wheel to drive the same is a gear 16.

The required slow drive to the timer wheel is taken off shaft 2, through chain 17 to shaft 18; from worm 19 on that shaft to shaft 20 through worm wheel 21; from shaft 20 through worm 22 to worm wheel 23 on shaft 24; and from pinion 25 on that shaft to gear 16.

In accordance with the stated object, this gear train is selected to effect one revolution of gear 16 (and the timer wheel) during the calculated number of revolutions of spindle 1 necessary to wind a package containing the desired yardage. In this connection it will be noted that shaft 15 on which the timer wheel unit is mounted, is supported in a bracket 26 which is adjustably mounted on a frame member 27, so that different size gears can be substituted for gear 16 to secure the required single turn of the timer wheel for different numbers of spindle turns as may be required.

Mounted on the timer wheel is a cam 28 which is adapted through suitable means to effect the release of the detent mechanism at the conclusion of a winding operation and thereby stop the winder.

In this preferred form the cam is located between discs 13 and is pivotally mounted on a stud 29 with freedom for limited movement relatively to the discs. The extent of movement permitted the cam is determined by the engagement of its inner edge with hub 14, the dotted and full line positions of the cam in Fig. 5 indicating the extent of this movement.

The means through which the cam operates to effect the release of the detent mechanism includes an actuating member in the form of a rod 30 supported in a bracket 31 secured to the outer end of arcuate arm 8. The upper end of the rod is bent over so as to overlie the timer wheel and carries a roller 32 normally located (i. e. during winding) in the path of that portion of the cam which projects beyond the periphery of the timer wheel discs.

As above stated, Fig. 1 shows the parts in the

running position, the timer wheel rotating in the direction of the arrow; and, as such rotation continues, the cam engages roller 32 and forces rod 30 upwardly, thereby raising arcuate arm 8 and disengaging the detent mechanism. Thereupon the winder drive is automatically disengaged by the usual spring clutch mechanism, handle 3 and its associated parts assuming the position shown in Fig. 2, and the spindle and drive shaft 2 coming to rest.

Referring more particularly now to Figs. 4 and 5, the former view illustrates the approximate position of the cam and roller at the instant that latch piece 5 on arm 6 is withdrawing from behind shoulder 7. At this instant the roller is substantially at or close to the top of the cam rise. The exact setting is not particularly critical and can readily be achieved by the adjustment of the rod in its bracket 31 in which it is secured by set screw 33. As the latch piece 5 continues its movement it wipes across the face 34, rotating about the axis of shaft 4 in an arc which causes it to cam arm 6 to a slightly still higher position than that achieved by cam 28. In so doing, it raises rod 30 and roller 32 to a point where the latter is out of contact with and outside of the path of cam 28 (see Fig. 5.) By a suitable spring or any other convenient means the cam is suitably biased so that as soon as the roller is raised out of its path it moves forward about its pivot from the dotted to the full line position of Fig. 5. In the present instance, as will be observed, the cam is so balanced as to fall forward of its own weight. As will also be observed, the position which the cam thus immediately and automatically assumes is beyond the roller, i. e. in the direction of rotation of the timer wheel, so that when the roller returns to its normal position the timer wheel is free to start, and complete, another full revolution before the cam again engages the roller.

Thus, by the foregoing or equivalent means, the yardage control mechanism is rendered fully automatic, not only is no manual resetting required but also no special attention or operations required of the operator other than the normal manipulation of the control handle. And, as above stated, the control functions to maintain the predetermined package content, according to the selected size of gear 16, within remarkably small limits.

Being of standard construction and operating in the usual manner, the drop wire action serving to stop the winder in the event of yarn breakage has not been described; but, as will be observed, the drop wire control and the yardage control, though both acting on or through arcuate arm 8, operate independently and without effect upon each other.

The following is claimed:

1. In a yarn winder having detent mechanism adapted to be disengaged to stop the winder, the combination of a timer wheel geared to the winder to make one complete revolution during the winding of a complete package, detent release means, and a cam mounted on the timer wheel to rotate therewith and with freedom for limited movement relatively to the wheel, said release means including a member adapted to be engaged by said cam.

2. In a yarn winder having detent mechanism adapted to be disengaged to stop the winder, the combination of a timer wheel geared to the winder to make one complete revolution during the winding of a complete package, detent release means, a cam mounted on the timer wheel to rotate therewith, said release means including a member normally located in the path of the cam and means

responsive to the operation of said release means to move said member out of the path of said cam.

3. The combination of claim 2 in which the cam is mounted on the timer wheel with freedom for limited movement relatively thereto and is biased to move past the said member when the latter is moved out of the path of said cam.

4. In a yarn winder having detent mechanism adapted to be disengaged to stop the winder, the combination of a pair of spaced discs geared to the winder to make one revolution during the winding of a complete package, a cam mounted with freedom for limited movement relatively to the discs in the space between them and protruding beyond the periphery of the discs, and detent release means including a member overlying said discs in the path of the cam.

5. In a mechanism for the purpose described, the combination of a latch, an actuating member therefor, means for moving said actuating member to a position to cause the release of said latch, and means responsive to the release of the latch to disengage said first-mentioned means from the actuating member.

6. In a mechanism for the purpose described, the combination of a latch, an actuating member therefor, cam means for moving said actuating member to a position to cause the release of said latch, and means responsive to the release of the latch to move the actuating member relatively to the cam.

7. In a yarn winder having detent mechanism adapted to be disengaged to stop the winder, the combination of a timer wheel geared to the winder, detent release means, and a cam mounted on the timer wheel to rotate therewith and with freedom for limited movement relatively to the wheel, said release means including a member adapted to be engaged by said cam.

8. In a mechanism for the purpose described, the combination of a timer wheel, a cam associated therewith, a latch, a latch-release member located in the path of the cam and adapted to ride the cam surface to a position to release the latch, and means responsive to the release of the latch adapted to move said member clear of the cam surface.

9. In a yarn winder having detent mechanism adapted to be disengaged to stop the winder, the combination of a timer member, a cam mounted thereon with freedom for movement relatively thereto from an actuating position to another position, a latch, a release member therefor located for engagement by the cam when the latter is in its actuating position, and means responsive to the release of the latch by said member whereby the cam is moved to its said other position.

10. In a yarn winder having release mechanism responsive to a predetermined number of revolutions of the winder, the combination therewith of a rotary member adapted to rotate along with said winder, a latch, an actuating member for said latch, means associated with said rotary member adapted to engage and move said actuating member in a direction and to a position to cause the release of said latch, and means for moving said actuating member in the same direction and to another position following the operation of said first-mentioned means, thereby to completely disengage said actuating member from said first-mentioned means.
